INFANT'S COMBINED BIB AND BOTTLE HOLDER

Herbert Daust, St. Louis, Mo.

Application August 16, 1950, Serial No. 11,781

Term of patent 14 years

(Cl. D3—26)

To all whom it may concern:

Be it known that I, Herbert Daust, a citizen of the United States, residing in the city of St. Louis, State of Missouri, have invented a new, original, and ornamental Design for an Infant's Combined Bib and Bottle Holder, of which the following is a specification, reference being had to the accompanying drawing, forming a part thereof.

In the drawing:

Fig. 1 is a plan view of an infant's combined bib and bottle holder, showing my new design, and

Fig. 2 is a side view thereof.

I claim:

The ornamental design for an infant's combined bib and bottle holder, as shown.

HERBERT DAUST.
